ELECTRICAL PLUG CONNECTORS

Joseph W. Focosi, 5119 N. Nagle Ave., Chicago 30, Ill.

Filed July 22, 1957, Ser. No. 673,256

1 Claim. (Cl. 339—182)

This invention relates in general to an automotive accessory plug and is more particularly described as an electrical plug connector adapted to make electrical connection with an electric outlet socket now usually installed on automobile panel boards for use with cigarette lighting and electrical equipment, but which may have a more general application with any electric lighting socket.

The electric socket now commonly installed upon the front panel board of an automobile and sometimes in other accessible places may now be used for connecting and illuminating automobile safety flares and signals, heating baby bottles, operating electric shavers and other similar uses as well as for the installed cigarette lighters.

In the present application, a quick acting accessory plug is provided which may be inserted or slipped readily in place which will tightly engage the center and a side contact of the socket by simply sliding the plug into position, and at the same time providing an outer handle for inserting and removing the plug.

An important object of the invention is to provide an accessory plug in which both contacts are spring pressed so that the plug may be pushed or slipped into engagement with a sliding movement instead of a rotary movement;

A further object of the invention is to provide an accessory plug having a portion serving as a handle for inserting and removing the plug from its connection with a socket; to provide improved means for connecting the contact elements of the plug with wire conductor terminals; to provide improved means for attaching contact members at the ends of conductor wires; to provide improved means for producing and attaching conductors to the ends of conductor wires; to provide improved terminals for self-locking engagement; and to provide a construction for reversing polarity when desired.

Other objects of the invention will be apparent from the accompanying drawings, in which,

Fig. 1 is a perspective view of an accessory plug in accordance with this invention;

Fig. 2 is an enlarged split view of an accessory plug casing as shown in Fig. 1, showing the conductors within the plug and the conductor wire attachments thereto as the plug is applied in a socket;

Fig. 3 is a fragmentary view of an improved conductor fastening; Fig. 4 is a perspective view of a modified conductor terminal; Fig. 5 is a perspective view of conductor terminal with a straight tip;

Fig. 6 is a perspective view of a portion of a strip of conductor contacts; and Fig. 7 is a perspective view showing the contacts of Fig. 6 as applied to the ends of conductor wires;

This accessory plug is made of complementary halves with conductors assembled in one part and the two parts then riveted or otherwise tightly connected together with provisions for securely attaching contact at the ends of the conductors inserted through openings at the end of

2

the casing. The contacts are attached to the ends of the conductors before they are inserted in the casing.

Referring now more particularly to the drawings, this plug connector comprises two similar casing parts 10 and 12 which when placed together have a longitudinal split forming a circular contact portion at one end and a somewhat flattened handle portion at the other end and the longitudinal split is on a substantially diametric central plane for assembling the parts in the casing. These 10 casing parts 10 and 12 are of hard plastic or other other suitable non-conductors and are substantially hollow at the inside except for certain connecting operating parts.

In one end of each casing part is a semi-circular recess 14 for seating a circular contact tip 16 therein, the casing part having a cross partition 18 spaced a short distance within this end and also having a recess 20 there-in for seating the tip. At the inner end of the tip is a flange 22 which bears against the inner side of the partition 18 and is held in resilient engagement therewith by a bent spring contact 24 firmly attached at one end to the inner end of the tip. The outer end of the tip 16 is rounded to make a good electrical engagement.

At one edge of the casing 10 is an inwardly recessed flat portion 26 having slots 28 and 30 at the ends and inwardly extending projections 32 and 34 at the ends of the flat portion 26. This provides an inwardly opening recess 36 into which a sharp angular bend 38 of the spring contact 24 and is movable freely back and forth therein. The other end of this contact 24 has an angularly bent extremity 40 hooked around a post 42 formed in the handle end of the casing. The spring contact 24 being made of metal, resiliently presses the flange 22 of the tip 16 against the partition 18 and any depression of the tip causes the angular bend 38 to move freely back-ward in the recess 36.

Another bent spring metal contact 44 has an angularly offset portion 46 which projects outwardly through the slot 30 on the outside of the flat portion 26 and inwardly through the slot 28 with one bent end 48 disposed 40 within the casing and engaging the inner side thereof ad-jacent the cross partition 18. The other end of this spring contact 44 is hooked around a post 50 and has an angularly bent extremity 52 extending inwardly from the post. The flat portion 26 and the projections 32 and 34 45 provide means for spacing the metal contacts 24 and 44 apart and also eliminate arcing of the current between them.

Between the posts 42 and 50 is a longitudinal partition 54 with a connected cross piece 56 at the inner end, the 50 partition 54 and the posts 42 and 50 being of a length to extend above the split line between the casing parts and to extend into corresponding recesses (not shown) in the casing part 12. Also at the other end of the plug are two projections 58 which register with recesses (not 55 shown) in the other casing part 12, these projections and the partition serving to register and position the casing parts in alignment. In order to secure the casing parts with the spring contacts therein tightly together, a screw or rivet 60 is inserted through registering perforations in 60 bosses 62 located centrally of the casing parts and the ends of the rivets or the other fastening means are seated in the recesses 64 in the outer sides of the casing parts.

In order to prevent the spring contacts 24 and 44 from moving away from their respective posts 42 and 50, ribs 66 and 68 are provided near the handle end of the plug connector which extend up close to the respective posts 42 and 50, but are separated from the posts by slots 70 and 72 respectively into which the edges of the spring contacts 24 and 44 are seated, the angular bent extremities 40 and 52 bearing resiliently but against the inter-mediate partition 54 which separate them when there are 70 no conductors attached to the plug.

In order to connect a pair of conductors 74 and 76 of the twin connected type and preferably having stranded copper wires 78 in the plug, each conductor has a terminal 80 (Figs. 2 and 7) with portions 82 wrapped around the extremity of the wire insulation of the conductor and teeth 84 formed up of the material between the wrapping portions 82 so that when these portions are crimped upon the insulated end of the conductor, they will penetrate the wrapping and will engage the stranded wires 78 making a satisfactory electrical connection therewith. The outer end of each terminal 80 has a flat portion 86 with an angularly bent extremity 88.

In Fig. 4, a terminal 81 is shown having teeth 83 at the sides bendable over the insulation 74 of a conductor and having smaller teeth 85 at the sides bendable over stripped metal wires at the end of the conductor. A portion 87 is curved instead of flat and an extremity 89 is bent angularly to the adjacent curved portion 87. This contact makes a firm engagement with the bent extremities 40 and 52 of the spring contacts when inserted in the end of a plug.

In applying these terminals 80 (and 81) to a pair of connected conductor wires, the flat portions 86 are at the insides and the bent extremities 88 extend outwardly so that when these conductors are to be connected into the plug, the terminals 80 are inserted in the handle end of the plug at opposite sides of the partition 54 and are pushed inwardly against the bent extremities 40 and 52 of the spring contacts 24 and 44 respectively as shown more clearly in Fig. 2 so that these bent extremities extend over the ends of the bent extremities 40 and 52 and are pressed by them tightly against the partition 54 holding the terminals and conductors attached thereto tightly in place and in good electrical contact.

The terminal 80 as shown in Fig. 5 is made up of a flat extremity 86 and the wrapping portion 82 which is applied to a conductor is shown with the teeth 84 indented inwardly. The outer flat portion 86 may be formed without the outer bent extremity 88 and if inserted in a plug in such condition, the terminals attached to conductors are held by the resilient engagement of the bent extremities 40 and 52 but conductors with the bent ends 88 and 89 are held much more firmly in position.

In order to provide terminals which are tightly lodged in place and also make improved contact engagement, terminals 90 and 81 as shown in Figs. 3 and 4, the contact portions of which are formed with curves 87 or angular waves 92 and 94 adapted to seat the bent extremities 40 and 52 of the spring contacts 24 and 44 between the waves of each terminal, making firm electrical connection with the spring contacts.

In all forms of terminals 80, 81 and 92 as shown by Figs. 2, 3 and 4, the inserted extremities of these terminals engage the connected cross piece 56 and prevent or limit the insertion of the terminal contacts beyond the cross piece, the engagement of the bent extremities prevent withdrawal of the terminals.

At the end of the plug opposite the contact 16, it is formed with opposite inwardly rounded grooved portions 95 and with opposite flattened sides 93 at right angles thereto so that the plug may be tightly gripped and inserted in close quarters and forming forefinger and thumb engaging portions. The flattened portion of the handle is marked with + (plus) indicating the polarity of the contact tip connection, and - (minus) indicating the polarity of the offset projection portion 46. The plug 16 when inserted in a socket 100 will always cause engagement of the plug with a central contact 102 in the end of the socket and the offset portion 46 will always engage a wall portion 104 in the outer portion of a socket or receptacle. In making this engagement, it is not necessary to turn the plug into the socket, but spring contact 44 to which the offset 46 is connected has sufficient resilience so that it will be held firmly but removably in the shell and the contact tip resiliently engaged with the cen-

tral contact 102. In removing the plug, it is pulled straight out, the offset portion 46 yielding or springing inwardly as the plug is removed.

Some automobiles are now equipped with 12 volt batteries and some still have 6 volt batteries. The lighter receptacle socket 100 for a standard 12 volt battery is smaller (by .028 of an inch) than a standard 6 volt socket, and a 6 volt accessory plug is provided with a round protrusion 101 which projects approximately .025 of an inch outwardly from the plug at the forward end of its thickest midsection portion. Near the handle end is a circle 103 with the designation 6v therein. The 12 volt plug is similarly marked 12v in the circle 103, and the universal plug with no protrusion has no marking.

In producing the contact terminals for the conductors, they may be stamped from a continuous strip 106 of material having ears 108 and formed with locating or positioning openings 110 at spaced distances apart. The tongues 84 are punched out of the material between the ears 108 and they may be offset oppositely at the same time if desired to form the opposite portions 82 which are bent about the conductors. Notches 112 are preferably formed between the side portions 82 and the flat portion 86 and the bent extremity 88 is preferably formed when the last terminal is cut from the strip. The terminal forming operation is thus continuous and is usually performed on an automatic machine, preparing the terminals for separate application to the ends of insulated conductors as shown. The terminals 81 having the teeth 83 and 85 are similarly produced.

Accessory plugs of this kind are thus prepared completely without any soldered connections; a firm electrical connection is made between conductors which are attached thereto; the terminals may be used for trouble lights, portable spotlights, bottle warmers, battery chargers, defrosters, electric fans and many other electrical automobile accessories. The plugs may also be used with other outlet sockets for making similar electrical connections for other electrical accessories. The terminals may be furnished separately in connection with conductors having connected terminals as shown, and they may also be furnished with terminals which are applied to other conductors connected to the desired accessories.

While a preferred construction has been described in some detail, it should be regarded by way of illustration and example rather than as a restriction or limitation thereof, as many changes in the construction, combination and arrangement of the parts may be made without departing from the spirit and scope of the invention.

I claim:

An electrical accessory plug for a socket having an inner end contact and a shell insulated therefrom, comprising a longitudinally split hollow insulating casing, a pair of spring strip contacts mounted in the casing having bent portions and adapted to flex therein, means in the casing engaging one end of each contact to hold them firmly and in spaced relation, one contact having a slideable tip at the other end of the contact projecting from the end of the casing to resiliently engage the inner end contact of a socket, the other strip contact having an angular offset near its other end projecting laterally from and depressible in the casing to make a resilient connection with the shell of the socket, means to contact the said engaged ends of the contacts in the casing and extending therefrom to provide electric circuit connections, said slideable tip having a flange at a distance from the end and inside of the casing, and the casing having a perforated cross partition through which the tip extends and the flange engages the inner side of the partition to limit the outward sliding movement of the tip pressed outwardly by the bent portion of the resilient strip contact, the hollow interior portion of the casing providing a space to receive the bent portion transversely thereof, the interior of the casing having a flat

portion adjacent the angular offset of said strip for spacing the strip contacts apart and inward projections at the ends of the flat casing portion forming an inwardly opening recess to receive the extremity of said bent portion to guide and limit the movements of said strip contact and the tip as it is moved back and forth.
